UNITED STATES PATENT OFFICE.

HERMAN F. BALL, OF BRONXVILLE, NEW YORK, ASSIGNOR TO ECONOMY DEVICES CORPORATION, OF NEW YORK, N. Y., A CORPORATION OF NEW YORK.

SAFETY DRAW-BAR.

1,231,473.

Specification of Letters Patent. Patented June 26, 1917.

Application filed February 27, 1917. Serial No. 151,213.

To all whom it may concern:

Be it known that I, HERMAN F. BALL, of Bronxville, in the county of Westchester and State of New York, have invented a certain new and useful Improvement in Safety Draw-Bars, of which improvement the following is a specification.

My invention relates to means for detachably connecting a locomotive engine and tender, and its object is to provide a supplemental or safety draw bar, the movement of which is coincident with that of the main draw bar, but which will not be dependent upon the draw bar pins, or main draw bar, for support, and will therefore be operative in the event of the breakage or displacement of the main draw bar or the draw bar pins.

The improvement claimed is hereinafter fully set forth.

In the accompanying drawings: Figure 1 is a plan view, partly in horizontal section, of the middle portion of the adjoining ends of a locomotive and tender, illustrating an application of my invention; Fig. 2, a vertical longitudinal central section through the same; and, Fig. 3, a view, the right hand half of which is a front elevation of so much of the appliance as is located on the tender, and the left hand half, a vertical transverse section, on the axial line of the tender draw bar pin.

In Letters Patent of the United States No. 1,223,553, granted and issued to me under date of April 24, 1917, I have set forth an improvement in draw bar pin castings, for application in connection with which, with certain structural modifications hereinafter noted, my present invention is particularly designed, and which, as so structurally modified, will be herein sufficiently described to explain the relation of my present invention thereto.

In the practice of my invention, referring descriptively to the specific embodiment thereof which is herein exemplified, the locomotive and tender are, as heretofore, and as in my Letters Patent No. 1,223,553 aforesaid, connected by a main draw bar, 1, which is coupled to the locomotive by a pin, 2, passing through a pocket, 3^a, on the foot plate, 3, and to the tender, by a pin, 4, passing through a draw bar pin casting, 5^a, 5^b, 5^c, 5^d. The draw bar pin casting is, under my present invention, horizontally

divided into two sections, which are fitted detachably together, and, when so fitted, constitute a box formed member, of substantially rectangular section, which is located between the side walls of a draw head, 6, rigidly secured to the center sills, 7, and front end sill, 8^a, of the tender. The casting is supported on carry irons, 7^a, secured to the draw head by bolts, 7^b.

The draw bar pin casting comprises an upper plate, 5^a, and a separate lower plate, 5^b, said plates having vertical side plates, 5, formed upon them, which abut in the horizontal plane of division of the casting, and being vertically perforated, in line axially, to receive the draw bar pin, 4. The two sections of the draw bar pin casting abut, at their forward ends, against lateral stops, 6^a, formed on the draw head, 6, and are forced against said stops by keys, 8, abutting on their rear ends and on the rear vertical transverse wall of the draw head, and drawn to proper bearing by bolts, 9, and nuts, 9^a.

A hub or boss, 5^d, is formed on the lower plate, 5^a, of the draw bar pin casting, and a similar hub or boss, 3^b, is formed on the bottom of the pocket, 3^a, of the foot plate of the locomotive. The openings of these hubs are concentric with the openings in the castings in which the draw bar pins are fitted. An auxiliary or safety draw bar, 10, having eyes, 10^a, and 10^b, in its ends, is fitted on the hubs, 5^a and 3^b, the diameters of the eyes being slightly greater than those of the hubs, so that the safety draw bar shall not be normally under tension. The main draw bar, 1, which is fitted on the coupling pins, 4 and 2, in the ordinary manner rests on the tops of the bosses, 5^a and 3^b, and the coupling pin, 4, being inserted from below, it is prevented from dropping out by a removable plate, 4^a.

The ordinary safety chain and pin coupled safety draw bar are unsatisfactory in practice, for the reason that in order to permit of curving, it is necessary to provide considerable slack, and in the event of failure of the draw bar or coupling pins, one or the other of the draw bars is subjected to the entire stress, or the locomotive and tender are parted. As heretofore constructed, it has not been practicable to make these parts sufficiently strong to at all times withstand the stresses imposed, or to guard against parting by breakage of a coupling pin. By

my invention, ample sectional area may be provided in the auxiliary draw bar to withstand the emergency stresses that may be imposed, and in the event of the breakage 5 of a coupling pin, said bar will maintain the connection of the locomotive and tender.

I claim as my invention and desire to secure by Letters Patent:

1. In a railroad vehicle draft gear, the 10 combination of a draw bar pin casting adapted to be supported on a railroad vehicle; a draw bar coupling pin fitted in a socket on said casting; a main draw bar coupled to said pin and adapted to be coupled, at its opposite end, to another vehicle; and an auxiliary or safety draw bar coupled to a boss on the draw bar pin casting, surrounding the coupling pin socket, and independently of the coupling pin, and adapted to be coupled, at its opposite end, to another vehicle.

2. In a railroad vehicle draft gear, the 15 combination of a draw bar pin casting adapted to be supported on a locomotive tender; a draw bar coupling pin fitted in a socket on said casting; a main draw bar coupled to said pin; a coupling pin pocket

on a locomotive; a coupling pin fitting in said pocket and in the main draw bar; and an auxiliary or safety draw bar, coupled to 20 a boss on the draw bar pin casting, surrounding the coupling pin socket and independently of the coupling pin socket, and similarly coupled, at its opposite end, to the coupling pin pocket of the locomotive. 35

3. In a railroad vehicle draft gear, the 25 combination of a draw bar pin casting, horizontally divided into two separable sections, and adapted to be supported on a railroad vehicle; a draw bar coupling pin fitted in 40 sockets in said sections; a main draw bar coupled to said pin and adapted to be coupled, at its opposite end, to another vehicle; and an auxiliary or safety draw bar, coupled to a boss on the lower section of the draw bar 45 pin casting, surrounding the coupling pin socket below the bearing of the main draw bar on the coupling pin, and adapted to be coupled, at its opposite end, to another vehicle.

HERMAN F. BALL.
